UNITED STATES PATENT OFFICE.

FRED L. EMERSON, OF DENVER, COLORADO, ASSIGNOR TO THE DENVER ROCK DRILL MANUFACTURING COMPANY, OF DENVER, COLORADO, A CORPORATION OF DELAWARE.

DRILL-MOUNTING.

1,214,527.

Specification of Letters Patent.

Patented Feb. 6, 1917.

Application filed September 30, 1915. Serial No. 53,349.

To all whom it may concern:

Be it known that I, FRED L. EMERSON, a citizen of the United States, residing at Denver, in the county of Denver and State 5 of Colorado, have invented new and useful Improvements in Drill-Mountings, of which the following is a specification.

The present invention relates to mountings for drills, and more particularly to 10 the means for securing rock drilling machines to columns, column arms, or the like.

The primary object of the present invention is to provide a device of this kind, by 15 means of which a lateral, as well as a lineal adjustment of the drilling machine can be readily effected with respect to the hole being drilled. As is well known, much time is often lost in changing drill bits when it is difficult to get the bits past the side of 20 the machine in removing and replacing them. This is especially so with the larger types of drilling machines now in general use. It has also heretofore been the common practice to loosen the saddle and move

25 the machine in or out on the column arm or shaft bar when the drill bit was binding in the side of the hole. It furthermore happens quite often that the column or shaft bar is set too close or too far away from the

30 rock to use to the best advantage the change of bits provided. With the present device, a quick change of bits can be readily made without the necessity of altering the position of the saddle or mounting on the column

35 arm or shaft, and when the bit is binding in the hole, a quick alinement can be effected. Furthermore in case the column or shaft bar is not at the proper distance from the rock, an adjustment of the drilling machine

40 can be quickly made without the necessity of altering the position of the column.

A preferred embodiment of the invention is illustrated in the accompanying drawings, wherein:—

45 Figure 1 is a top plan view of the mounting. Fig. 2 is a vertical sectional view therethrough. Fig. 3 is a bottom plan view of the drill-holding member. Fig. 4 is a top plan view partially in section of the 50 upper clamp or support engaging member. Fig. 5 is a side elevation of the device, but illustrating the drill holding member reversed from the position shown in Fig. 2, in order to indicate the range of adjustment

that can be obtained. Fig. 6 is a rear elevation of the device with the parts as shown in Fig. 2.

Similar reference numerals designate corresponding parts in all the figures of the drawings.

In the embodiment illustrated, a column arm or shaft is shown at 7, and may be any well known type of support. Engaged with this support is a clamp comprising an upper member 8 and a lower member 9 having recessed portions 10 and 11 to receive said support 7. Bolts 12 connect the members on opposite sides of the support 7 and serve to secure the clamp in fixed relation upon said support in a manner well understood. 65 The upper support engaging member 8 is chambered as shown at 13, said chamber opening through the top of the member and being surrounded by an upstanding ring seat 14, the outer face of which is 70 tapered upwardly and inwardly, as shown at 15, while the inner face is vertical or perpendicular as shown at 16.

Rotatably mounted on the member 8 is a drill holding member 17. This member 80 is provided in its under side with a circular groove 18 that receives the ring seat 14, the outer wall of the groove being tapered as illustrated at 19 to correspond to the face 15, while the inner wall of the 85 groove is vertically disposed, as shown at 20 to correspond to the inner face 16 of the ring seat. This groove thus produces a boss 21 that fits within the upper portion of the chamber 13, and said boss has a 90 central opening 22 therethrough, communicating with a socket 23 formed in the member 17.

A clamping bolt 24 passes through the opening 22, and has a circular head in the 95 form of a nut 25 threaded upon its upper end and located in the socket 23. This nut is held against rotation by a key pin 26 engaged therewith and with the bolt 24, as shown more particularly in Fig. 1. The 100 lower end of the bolt 24 is located in the chamber 13 of the member 8 and has a pivotal connection 27 with an operating bolt or lever 28 arranged in the chamber 13 and pivoted therein as shown at 29. 105 This bolt projects through an opening 30 formed in one wall of the chamber 13, its projecting end being threaded and having

thereon a nut 31 which bears against a washer 32 interposed between the nut and the adjacent wall of the member 8.

The drill holding member 17 is formed in its upper side with a seat 33 to receive the usual base of an ordinary drilling machine, a portion of such base being shown at 34. This seat on one side is provided with a stop wall 35 undercut, as shown at 36 to receive the base flange. In order to secure the base in place, a clamping block 37 coöperates with the seat, and is disposed diametrically opposite to the central portion of the stop wall. This block has an opening 38, through which is passed a holding bolt 39, the outer end being threaded to receive a binding nut 40 and a washer 41 being interposed between the nut 40 and block. The inner portion of the bolt lies in a recess or groove 42 formed in the bottom of the seat and its inner end is in the form of a cross head 43 that detachably engages in a socket 44 also formed in the bottom of the seat. This cross head is tubular in form and is retained against accidental displacement by a pin 45 that passes therethrough and through the drill holding member 17.

It will be noted particularly by reference to Fig. 2 that the above described mechanism provides a rotatable mounting for the base of the drill, and that said drill can be fixed in any desired position therein. It will also be observed that the axis of rotation of the drill base is eccentric to the axis of rotation of the drill holding member 17. Consequently, if the parts, namely, the drill, the drill holding member 17 and the support engaging member 8 are relatively rotated, various adjustments can be secured. In order to provide convenient means for rotating the drill holding member, lugs 46 are preferably formed upon the same and may be engaged by the same wrench employed for operating the nuts 31 and 40. As illustrations of the manner in which the device may be operated, to change the drill bits or steel, all that is necessary is to loosen the two nuts 31 and 40 and swing the machine sidewise by revolving the member 14 a quarter turn, while maintaining the drilling machine parallel to its original position. Obviously this places the machine at one side of the hole so that the used drill bit can be withdrawn without interference and a new one entered, after which a reverse operation will bring the machine back to its operative position. When the drill steel is binding in the side of the hole, a quick alinement can be made by slackening the two nuts 31 and 40, and then by operating the drill piston slowly, the machine will adjust itself to bring the steel into correct alinement. If the column or shaft bar is set either too close or too far from the rock, a material adjustment can be secured by ro-

tating the member 17 upon the member 8, and if this is not sufficient, the position of said member 8 can be reversed and the range of adjustment thereby doubled.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, so what I claim as new and desire to secure by Letters Patent, is:—

1. In a device of the character set forth, a support-engaging member, a drill holding member rotatably mounted thereon, a clamping bolt disposed axially of the members, an operating lever pivoted to the support engaging member and connected to the clamping bolt for moving the same axially, and means for placing strain upon the lever.

2. In a device of the character set forth, a support clamp including a chambered member having an upstanding ring seat, a drill holding member rotatably mounted on said ring seat and having an axial socket, an axially disposed clamping bolt having a head in said socket, said bolt extending into the chamber, an operating lever pivoted in the chamber and connected with the lower end of the clamp bolt, said operating lever projecting from the member, and a nut on the projecting end of the lever having a bearing against the member.

3. In a device of the character set forth, relatively rotatable support engaging and drill holding members, a bolt disposed axially of the members and having an adjustable clamping head engaging one of the same, a lever pivoted to the bolt and having a pivotal mounting on the other member, and means for swinging the lever to effect a clamping action between the head and the member engaged thereby.

4. In a device of the character set forth, the combination with a support engaging clamp including an upper member having an internal chamber and an upstanding ring seat, of a drill holding member rotatable on said seat, means in the chamber and engaged with the drill holding member for clamping it against rotation and in different positions, said drill holding member having a recessed drill base receiving seat in its upper side disposed eccentrically to the ring seat, and means for rotatably mounting the base of a drill in the latter seat and clamping it against rotation and in different positions.

5. In a device of the character set forth, the combination with a support engaging

member, of a tool-holding member rotatably mounted thereon, a clamp bolt moveable axially of the tool holding member, means for moving the bolt, a clamping head 5 adjustably threaded on the bolt and engaging the tool holding member, and a pin connection between the bolt and head to normally hold them against relative rotation.

In testimony whereof I have hereunto set my hand in presence of two subscribing witnesses. 10
